[57] **CLAIM**

The ornamental design for a combined brush and scraper attachment for a faucet spray handle, as shown and described.

DESCRIPTION

FIG. 1 is a top perspective view of a combined brush and scraper attachment for a faucet spray handle showing our new design;

FIG. 2 is an enlarged side elevational view thereof, the opposite side being a mirror image;

FIG. 3 is a greatly enlarged right end elevational view thereof;

FIG. 4 is a left end elevational view thereof;

FIG. 5 is a top plan view thereof;

FIG. 6 is a bottom plan view thereof; and,

FIG. 7 is a bottom perspective view thereof.

The broken line showing of a faucet sprayer is for illustrative purposes only and forms no part of the claimed design.
